(57) **CLAIM**

The ornamental design for an angled connector for tubing, as shown and described.

DESCRIPTION

FIG. 1 is a right perspective view from the front and bottom sides of a first embodiment of an angled connector for tubing. FIG. 2 is a left perspective view from the top and back sides of the angled connector for tubing shown in FIG. 1.

FIG. 3 is a right side view of the angled connector for tubing shown in FIG. 1.

FIG. 4 is a front view of the angled connector for tubing shown in FIG. 1.

FIG. 5 is a left side view of the angled connector for tubing shown in FIG. 1; and,

FIG. 6 is a bottom view of the angled connector for tubing shown in FIG. 1.

The designations of the views below as top, bottom, right side, left side, front, and back are for ease of discussion only and are not intended to limit the angled connector for tubing to one particular orientation.
